UNITED STATES PATENT OFFICE.

CHARLES H. SIMMONS, OF CHICAGO, ILLINOIS, ASSIGNOR TO MILTON E. PAGE, JR., ADOLPH T. JOHANSON, AND CHRISTOPHER M. PAGE, ALL OF CHICAGO, ILLINOIS, TRUSTEES FOR AABALL MANUFACTURING COMPANY, A COMMON LAW TRUST.

ADJUSTABLE VALVE.

Application filed March 28, 1923. Serial No. 628,269.

To all whom it may concern:

Be it known that I, CHARLES H. SIMMONS, a citizen of the United States, and resident of Chicago, in the county of Cook and State 5 of Illinois, have invented certain new and useful Improvements in Adjustable Valves, of which the following is a specification.

My present invention concerns valves, especially those with adjustable characteristics, designed more particularly, but not restrictedly, for employment in connection with oil or other liquid fuel burners, whereby the fuel supply to the burner may be easily regulated without stopping the 15 movement of the burner when the latter is of the rotary or revolving form.

A further aim of the invention is the provision of an appliance of this kind which assists or aids in preventing the burner and 20 its pipe or conduit connections from becoming clogged or stopped up.

An additional purpose of the invention is to supply a structure having the functions specified which is simple in construction and 25 hence economical to produce and unlikely to become deranged, injured, or out of adjustment during ordinary service.

To enable those skilled in this art to have a full and complete understanding of the 30 invention and its various advantages in the accompanying drawings forming a part of this specification I have illustrated three embodiments of the invention and throughout the several views of this drawing like 35 reference characters have been employed for the same parts.

In this drawing,

Figure 1 is a sectional or broken view of 40 a rotary oil burner equipped with one embodiment of the improved valve;

Figure 2 is a fragmentary, vertical section of a different embodiment of the invention; and

Figures 3 and 4 are sections at right angles 45 to one another of another form of valve structure, Figure 4 being a section on line 4-4 of Figure 3, the parts being viewed in the direction indicated by the arrows.

The illustration in Figure 2 is on a somewhat larger scale than that shown in Figure 50 1 and the illustration in Figures 3 and 4 is on a still larger scale.

Referring first to the style of valve structure shown in Figure 1, it will be perceived

that the burner construction comprises a 55 base-plate 11 having an oil compartment or chamber 12 in which the fuel-oil, which also acts as a lubricant for the gearing, is maintained at a substantially constant level by a float-controlled valve governing the delivery 60 of the liquid through a supply pipe into the chamber.

Such supply pipe connection 13 extends through one of the side walls of the chamber and inside of the latter it is fitted with 65 a valve 14 of any suitable or appropriate construction actuated by a float 15 having a lever connection 16 with the valve, the lever being fulcrumed on the inside of the compartment wall at 17.

Such base-plate, outside of the chamber, has an electric-motor 18, the shaft 19 of which extends through a suitable bearing 21 into the interior of the compartment where it is fitted with a worm-wheel or spiral-gear 75 22 meshing with and rotating a companion, horizontal worm or spiral-gear 23 fixed on a vertical, hollow shaft 24 revoluble in bearings 25 and 26 on a standard 27 and projecting or extending up through an aperture 80 in the top wall 28 of the chamber.

At its top end, this hollow shaft or tubular member has a burner 29 into which the oil or other fuel fed up the shaft is delivered and by means of which, due to its rapid rotation, the oil and air are properly and thoroughly mixed or atomized.

The exact form and style of the rotary burner is immaterial so far as the present invention is concerned, and, consequently, no 90 further description of its structure or mode of operation is required.

Obviously, it is necessary or desirable to regulate or control the flow of liquid up through the upwardly extending or tapered 95 passage of the shaft, and, accordingly, the lower open end of the latter, through which it receives its fuel supply from the chamber, is equipped with a conical valve-seat 31 with which a correspondingly-shaped valve 32 100 coacts to open or close more or less the conduit through the shaft.

Such valve is mounted on one end portion of an arm or lever 33 fulcrumed or pivoted on a part of the standard at 34, the other 105 end of the arm or lever having an upright rod 35 pivoted thereto at 36, such rod extending up through a hole in the cover-plate

28 and being fitted beneath the latter with a collar 37 between which and the under surface of the cover-plate a coil spring, encircling the rod, is interposed.

5 Thus the spring yieldingly tends to move the valve to closed position against its valve-seat.

In order that the position of the valve may be easily and readily adjusted, the upwardly protruding end of the vertical rod has a collar 39 fastened to it, and beneath this, and bifurcated so as to straddle the rod, I employ a wedge 41 slideable on the top of the cover-plate, the position of the wedge being controlled by a screw shaft 42 mounted in a threaded bearing 43 on the cover-plate and equipped with a turning handle 44, the screw shaft being connected in any convenient manner to the wedge in such a way as 20 to be capable of independent rotation on its own axis.

Hence we have an easily manipulated or adjustable valve to regulate the oil flow up the bore of the rapidly-revolving, hollow, 25 vertically-disposed shaft, up which it is drawn by reason of the action of centrifugal force.

In this valve, one of these elements, the one with the port and the conical valve-seat, 30 is adapted to revolve rapidly, while the companion member or valve proper is relatively stationary, but yet adjustable to govern the extent of valve opening as may be required.

35 This is apparently a novel and simple construction permitting regulation or adjustment of the valve without stopping or interrupting the rotation and operation of the revolving burner.

40 In Figure 2, I have shown a somewhat modified or different form of structure, wherein the conical valve 50 constitutes the upper end of a vertically-slidable shaft 51, guided in alined bearings 52 and 53, both 45 in members mounted on the base plate of the oil chamber, and having rack teeth 54 cut in one side with which mesh the teeth of a gear 55 on a horizontal shaft 56 mounted in bearings 57 and 58 and extending 50 out through a side wall of the oil chamber through a stuffing-box 59, the external end of the shaft having a turning wheel or handle 61 by means of which the position of the valve may be regulated with facility.

55 In some cases, it is desirable to have the valve turn somewhat during its lengthwise adjustment and such a style of construction is depicted in Figures 3 and 4.

In this device, the valve 70 is formed on 60 the upper end of an upright, screw-threaded shaft 71 in a threaded bearing 72 and having a reduced-diameter, lower, cylindrical part 73 received in another bearing 74 on the base-plate of the oil chamber, the 65 complementary bearing 72 constituting part

of a bracket or support 75 mounted on such base-plate.

A gear 76 on the section 73 of the shaft between the two bearings is adapted to permit the shaft to slide therethrough, but between the gear and the shaft there is a key and slot or spline connection 77 by means of which the gear may rotate the shaft, the teeth of such gear being in mesh with those of a gear 78 on a shaft 79 mounted 75 and adjustable as is the shaft 56 of the other modification of the invention.

Consequently, when shaft 79 is turned the valve will be adjusted by both a longitudinal and rotative movement toward or 80 from its revolving valve-seat.

In all these species the passage in the shaft tends to be kept from becoming clogged, the reason for which action is not fully understood at the present time, but 85 it may in part be due to the fact that it seems to be desirable, although not absolutely essential, to so mount the valve and permit sufficient play in its operating parts, that it may flutter or vibrate slightly 90 during the action of the burner toward and from its revolving valve-seat.

Accordingly in some cases it is of advantage to mount the valve so that it may have the vibratory movement specified. 95

Those skilled in this art will readily understand that the invention is not limited and restricted to the precise and exact details of construction presented but that these may be modified within radical degree without departure from the heart and essence of the invention and without the sacrifice of any of its substantial benefits and advantages.

I claim:

1. In a structure of the character described, the combination of a member having a valve-port, means to revolve said member, a relatively-stationary valve cooperating with said port, and means to adjust said valve and member with relation to one another to vary the extent of port opening. 110

2. In a structure of the character described, the combination of an upright hollow shaft having an open lower end constituting a valve-port, means to revolve said shaft, a relatively-stationary valve cooperating with said valve-port, and means to adjust said valve toward and from said port. 115

3. In a structure of the character described, the combination of a chamber adapted to contain a lubricating liquid fuel, a hollow upright shaft open at its lower end constituting a valve-port, said shaft being partly in said chamber and partly outside thereof, a fuel burner on said shaft receiving its supply of liquid fuel through the passage of said shaft, gearing immersed in the liquid fuel in said chamber to rotate said shaft and its burner, means to operate 120 125 130

said gearing, a relatively-stationary valve cooperating with said valve-port, and means operable from the outside of said fuel-chamber to adjust the position of said valve relatively to said valve-port.

4. In a structure of the character described, the combination of a chamber adapted to contain a liquid fuel, a hollow upright shaft open at its lower end constituting a valve-port, said shaft being partly in said chamber and partly outside thereof, a fuel-burner on said shaft receiving its supply of liquid fuel through the passage of said shaft, means to revolve said shaft, a relatively-stationary valve cooperating with said valve-port, and means operable from

the outside of said fuel-chamber to adjust the position of said valve relatively to said valve-port.

5. In a structure of the character described, the combination of an upright hollow shaft having an open lower end constituting a valve-port, means to revolve said shaft, a relatively stationary valve cooperating with said valve-port, and means to adjust said valve toward and from said port and permitting the valve to have a vibratory movement toward and from the valve-port during the rotation of the shaft.

In witness whereof I have hereunto set my hand and seal.

CHARLES H. SIMMONS. [L. s.]
